UNITED STATES PATENT OFFICE.

GEORGE H. MALLARY, OF NEW YORK, N. Y.

IMPROVEMENT IN MACHINERY FOR MAKING PAPER BAGS.

Specification forming part of Letters Patent No. 80,298, dated July 28, 1868.

To all whom it may concern:

Be it known that I, GEORGE H. MALLARY, of the city of New York, county and State of New York, have invented certain new and useful Improvements in Machinery for making Paper Bags; and I do hereby declare that the following is a full, clear, and exact description thereof, reference being had to the accompanying drawings and the letters and figures of reference marked thereon, making part of this specification, in which—

Figure 1 is a top face view of my machine. Fig. 2 is a vertical longitudinal sectional view of the same cut through on the dotted line *a a* of Fig. 1. Fig. 3 is an end view of the same machine, showing the right-hand end of Figs. 1 and 2. Fig. 4 is a side view of the central portion of the frame of the machine detached, showing one end of the gate which carries the cutting blade or knife, and the cam by which it is moved. Fig. 5 is a detached end view of the apparatus, by which the bag, in process of making, is pasted and folded at the closed end. Fig. 6 is a vertical sectional detached view of the clamp by which the bag, in process of making, after being cut from the sheet, is moved forward to the end folding and pasting apparatus.

In the several drawings the same letters and figures refer to the same parts.

A is the frame, made of iron or other suitable material, which may be formed of two sides, each cast in one piece, set and held together by cross bars or rods *b* bolted or screwed to the sides. A plate of iron, *2*, constitutes a closed top or table covering a little more than one-half of the length of the frame. The balance of the top consists of the supporting-bars *u*, extending from the end of the plate *2* to the opposite end of the frame. Upon this frame the several parts of the machine are mounted.

B is the main driving-shaft, to which motion is communicated by a belt acting on the pulley *C*, and which rests in boxes in the sides of the frame *A*. In the center of this shaft is a crank, *c*, which actuates the swinging lever *D*, that is pivoted at *e* in a joint formed with the short post *f* set in the cross-bar *g*, the crank *c* working in the sliding box *h* held between the two branches *d' d'* of the lever *D*. *E* is a

second swinging lever, pivoted at *i* in the post *j* set in the cross-bar *k*, which is actuated by the lever *D* by means of the connecting-bar *F*, hinged at *l* to the short arm *m* attached to the lever *D*, and fastened to the lever *E* by the pin *n*, that passes through the end of the bar *F* and the mortise *o'* in the lever *E*. The object of this mortise is to permit the lengthening and shortening of the sweep of the lever *E* by raising or lowering the bar in the mortise. This lever *E* is connected with and communicates motion to the clamp formed of the bar *L* and the shaft *K*, with its lags *t*, by means of the short connecting-bar *I*, jointed into the arm *J*, extending from the rod or shaft *K*. This clamp is connected with a frame consisting of two side pieces *o* and *o'*, and the cross-bars *p* and *L*, the bar *L* forming at once a part of the frame and the upper jaw of the clamp. On the inner faces of the side pieces *o* and *o'* are ribs, which fit into grooves in the ways *r r'*, which are fastened on the inner side of the top rail of the frame *A*, in which the clamp can slide back and forth. In this frame, and immediately underneath the bar *L*, is a revolving shaft, *K*, extending from side to side of the said clamp-frame, to which is attached the arm *J*. On the top surface of this shaft is fixed a series of lags, *t*, wide enough to just pass between the supporting-bars *u*. The shaft *K*, with its lags *t*, constitutes the lower jaw of the clamp.

Upon the forward end of the machine is fastened a flat frame, *M*, cut out of a metal plate, designed to hold between its sides the paste-reservoir *N*, which is placed on short posts *Q*, thus raising it a short distance above the surface of the frame *A*.

R R are two guide-rollers, mounted in the arms *P P'*, the upper roller being adjustable by means of elongated boxes.

Near the center of the frame is arranged a knife, *S*, extending across the machine, its edge downward, fastened to the under side of the bar *T*. At either end of this bar *T* is a leg, *U*, extending downward on the outside of the frame *A*, between ways *v v'*. The lower ends of these legs, brought to a rounded edge, rest on cams *V*, fixed on the ends of the shaft *B*, the cams being eccentric.

By these means the knife *S* has given to it

a vertical reciprocating motion, it being raised by the cams and allowed to fall by its own weight.

Y is a slide, some three or four inches wide, placed between ways that are fastened to the under side of the table 2, midway between the sides of the frame A. On the under side of this slide Y is placed a smaller slide, W, and loosely connected with it by means of screw-bolts, with broad heads, passing through slotted holes. These slotted holes are made long enough to permit the movement of the slide W, of three or four inches, upon the slide Y. Hinged into the end 3 of the slide Y is a revolving jaw, 31, made in the form represented. The lower portion of this jaw constitutes a segment of a toothed pinion, which, with the toothed end of the slide W, forms a rack and pinion. It is evident that by this arrangement the movement of the slide W backward and forward on the slide Y remaining at rest, the jaw 31 will be revolved on its axis, alternately throwing its lip over onto the upper face of the slide W and then downward below the upper surface of the plate 2. It is evident, also, that when the slide W has reached the limit of its movement in the slotted holes, it will, if its movement be continued, communicate motion to the slide Y, giving to it a reciprocating movement after expending each way its own lost motion.

Upon the upper surface of the table or plate 2 are placed two folders, 6 and 6'. These are formed of flat bars of wood or iron, or other material, screwed down upon the table at a distance apart corresponding to the width of the bag. Their under inner edges are cutaway so as to form grooves deep enough to permit two thicknesses of paper to pass through them, and at the ends toward the knife S are enlarged laterally and vertically with a gradually expanding twist, so that, when a sheet of paper is drawn in under them, the sides or edges will be gradually folded over and laid down underneath the lips of the folders.

4 is a shaft, on which are placed two cams, 5 and 5', the faces of which are cut away around about one-half their circumference, so that they will act upon the paper passing under them only during a part of their revolution. This shaft 4 is actuated by a belt from the pulley 10 on the pulley 9 and the gears 7 and 8. The wheel 7 has teeth upon only one-half its periphery, thus allowing the shaft 4 to remain at rest during one-half of the revolution of the wheel 7.

12 is a paste-reservoir, having a longitudinal opening near the bottom on one side, through which opening a portion of the periphery of the pasting-roller 13 extends into the reservoir, thus lying in contact with the paste, and is so adjusted as to so nearly fill the opening that the paste will not escape, and yet permit a portion to be taken up on the surface of the roller and carried out. To this roller is given an intermittent rotary motion by means of a

ratchet-wheel, 14, and a pawl attached to the cross-head Z, which in its upward and downward motion revolves the roller 13 one notch of the wheel 14 at each movement.

Z is a cross-head moving in ways fixed on the plate 16 at the end of the machine, to which a vertical reciprocating motion is given by means of the lever G and the cam 17. This lever swings on the shaft 18, and is connected with the cross-head by the link 19. The office of this cross-head is twofold, viz., to carry the end-lap of the bag against the pasting-roller 13, and turn the said lap over preparatory to its entering between the rollers 21 and 21', to be by them pressed and closed. The upper edge of the cross-head is beveled so as to fit the curve of the roller 13, which enables it to press the lap of the bag against the roller, so as to take up sufficient paste to fasten it, at the same time that it turns it over the edge of the folding-blade 15 attached to the upper face of the table 2, just underneath the roller 13.

To the end of the machine in front of the cross-head Z is a pair of rollers, 21 21', held by the arms 20, the upper one of which receives motion from the shaft B by a belt on the pulleys 22 and 23. The upper roller is held in slotted boxes, which permit it to be adjusted to the varying thicknesses of the paper passing between them.

34 and 34' are two spring-guides, designed to guide the paper into the folders and assist in the process of folding. They are attached to the cross-bar 38, which is held by the arm 33 connected to the bar 35.

The table or plate 2 is cut away from the end back as far as the jaw 31 traverses wide enough to permit the passage of the said jaw.

The operation of this machine is as follows: The paper is in a continuous sheet, wound into a roll, and placed on a convenient reel. The end is introduced between the rollers R R', and carried forward over the supporting-bars u between the jaws of the clamp L t. The movement forward of the lever E will then close the said clamp by rolling the shaft K on its axes and bringing the lags t up against the bar L. The paper thus held is then carried forward toward the knife S a distance determined by the connection of the lever E with the crank c. When the lever E commences its backward movement, its first action is to rock the shaft K backward, thus swinging the lags t downward and away from the bar L, thus liberating the paper, which remains at rest, while the clamp moves back to its limit and again takes hold of the paper and moves it forward underneath the knife S; a piece of paper is then cut off of suitable length for a bag, the edge of the knife passing through the paper into a narrow slot or opening, 36, in the table. As soon as it is cut from the sheet, the piece is seized by the clamp 31 and drawn forward into the folders 6 and 6', which fold the sides over so that

the edges meet and lap in the center far enough to form a seam, the forward end of the bag having been carried forward far enough to bring the lap at the end just under the pasting-roller 13. The reverse movement of the slide W then opens the clamp-jaw 31, which swings forward and downward below the surface of the table 2, thus liberating the bag, and then moves back to take hold of another piece that has just been cut off. The cross-head Z then moves up, pressing the end-lap of the bag against the pasting-roller 13, and at the same time turns it upward over the edge of the folding-blade 15, so that when the bag is moved forward between the pressure-rollers 21 and 21', which is done by the cams 5 and 5', that, impinging upon the upper surface of the papers, are brought into action at the right moment, the lap is pasted firmly down upon the bag, forming the closed end. By the passage of the bag between these rollers, the side seam is also pressed and pasted firmly together, and the bag is delivered from the rollers completed. The paste for the side seam is deposited near one edge of the paper in its progress through the machine by means of a pasting device in the paste-reservoir N, which is adjusted over the side of the sheet at the proper place. This device may consist of a disk or thin wheel arranged to rotate in the bottom of the reservoir, a portion of its periphery extending

through an opening in the bottom of the reservoir and resting on the paper. As the paper moves forward, the disk is caused to revolve, and deposits on the paper a line of paste.

The lap forming the closed end of the bag is formed by having the knife S bent so that the paper is cut at the center of the sheet a distance equal to the width of the folded bag, somewhat longer than at the sides.

What I claim as new, and desire to secure by Letters Patent, is—

1. The clamp formed of the bar L, the shaft K with its lags t, when combined with the supporting-bars u, substantially as set forth.
2. The clamp formed of the slides W and Y, and the jaw 31, when combined with the folders 6' and the cams 5 5', substantially as described.
3. The cross-head Z, the folding-blade 15, and the pasting-roller 13, combined and arranged substantially as described.
4. The levers D and E, the crank c c, the clamp formed of the bar L, and the shaft K, with its lags t, and the clamp formed of the slides W and Y and the jaw 31, all combined and operating substantially as described.
